UNITED STATES PATENT OFFICE

GUSTAVE M. NELL, OF DETROIT, MICHIGAN, ASSIGNOR TO CHICAGO PNEUMATIC TOOL COMPANY, OF NEW YORK, N. Y., A CORPORATION OF NEW JERSEY

SLIP ROTATION APPARATUS

Application filed April 6, 1929. Serial No. 353,206.

This invention relates to rock drilling machines and tools, with particular reference to the mechanism by which the drill steel is rotated or stepped around during the drilling operation.

With conventional rock drills of the self rotating type using rifle bar mechanism, the sticking of the drill steel tends to cause the entire machine to rotate. If the tool is hand

10 supported the operator can resist such movement and shut off the air. But in the case of the self rotated stoper the guiding handle is sometimes whipped out of the operator's hand and as the machine rotates it winds up 15 the hose and may injure the operator before he can get the machine under control. The stuck steel must then be loosened and in forcibly rotating or rocking the machine or in using a bar in the handle or other 20 opening in the machine to secure a leverage, the rotation mechanism is often subjected to a strain beyond its strength with the result that the rifle bar breaks or the threads holding the rifle nut in place are stripped.

25 One object of the invention is to prevent damage to drills and injury to operators when drill steels become stuck. Another object is to provide for release or slipping of the rotation mechanism when subjected to excessive strain. Another object is to devise 30 simple and inexpensive mechanism for securing the above results, which mechanism is readily adaptable to old as well as new machines. Other objects will be apparent 35 from the detailed description which follows.

The invention involves means for causing 40 a slip in the rotation mechanism, as between the rifle bar nut and the piston, so as to minimize, or entirely to prevent, rotation of the machine as a whole when the drill steel is under abnormal torsional load or becomes stuck, but which will provide for rotation of the drill steel under normal conditions.

45 By preference the slip grip or friction in the rotation mechanism is made proportional to the torsional strength of the parts most likely to break, so that slip will occur before these parts are overloaded or unduly strained.

50 In order to illustrate the invention one

concrete embodiment thereof is shown in the accompanying drawing, in which:

Fig. 1 is a fragmentary sectional view of so much of a rock drill as is necessary for the understanding of the invention;

Fig. 2 is a transverse sectional view through the piston shown in Fig. 1 substantially on the line 2—2 of Fig. 1; and

Fig. 3 is a right end elevational view of the piston.

The embodiment of the invention chosen for the purpose of illustration, discloses a portion of a fluid pressure, self-rotating rock drill having a cylinder A in which reciprocates an impact member or piston 4 arranged to deliver blows as well as to impart rotation to a drill steel (not shown). The reciprocatory movement of piston 4 is utilized to effect rotation of the same through mechanism of the rifle bar type which includes a rifle bar 5 suitably supported in the rear end or back head (not shown) of the drilling machine and extends axially of the piston chamber to cooperate with a rifle nut 6 supported in a recess 4a in the rear end of the piston, which recess has a reduced extension 4b to receive bar 5. The rotative impulse imparted to piston 4 is transmitted by ribs or flutes 4c on the latter in sliding engagement with similar flutes b on a chuck B into which the drill steel (not shown) extends.

In order to prevent breakage of the parts of the rotation mechanism, or injury to the operator due to the rotation of the entire machine in the event of a stuck steel, a slip connection is provided somewhere in the rotation train. By preference this slip connection takes the form of a flexible and automatically detachable coupling which is provided

on piston 4. To this end nut 6 has a smooth annular exterior which is journaled in the smooth annular bore of a retainer 7 which takes the form of an externally threaded sleeve for cooperative threaded engagement with the internal threads of recess 4a of piston 4. On its inner end, retainer 7 has a recess 7a of greater diameter than its bore to receive a radial flange 6a on nut 6, which flange is clamped against the bottom of recess 4a when

retainer 7 is set up tight. The flexible and detachable coupling is by preference arranged between nut 6 and retainer 7 and may take the form of a flat spring 8 encircling 5 flange 6a of nut 6 and seated in recess 7a of retainer 7. One end 8a of spring 8 is in-turned and seats in a shallow slot 6b (Fig. 2) of nut 6 while the other end 8b is engaged in a slot 7b in retainer 7.

10 The rifle nut, retainer, spring assembly (6, 7, 8) is inserted as a unit in recess 4a of piston 4, a wrench being applied to flats 7c (Fig. 3) on the head of retainer 7. The screw threads are in the proper direction to cause retainer 15 7 to screw into the piston under the impulse or reaction of the rotation mechanism and to take up any clearance between the flanged head 6a of rifle nut 6 and the bottom of recess 4a so as to prevent relative longitudinal 20 movement of nut 6. The intensity of this clamping action is limited by the amount of rotational impulse transmitted by the flexible coupling effected between nut 6 and retainer 7 by spring 8, and it is obvious that as the 25 friction between the bottom of recess 4a and flange 6a of the nut increases, there will be a decrease in the screwing up impulse transmitted to retainer 7. Hook end 8a of spring 8 and the cooperating recess 6b in rifle nut 30 6 are so formed and of such extent as to transmit through coupling spring 8 sufficient impulse for normal rotation requirements but hook end 8a will release or slip out of recess 6b when the rotative impulse 35 exceeds a predetermined amount or becomes excessive through the sticking of the drill steel.

I am aware that protection of the rotative mechanism may be secured otherwise than 40 by providing the flexible connection between the rifle nut and the piston, and that other forms of slip and frictional engaging arrangements may be used without departing from the spirit of this invention. I therefore 45 do not desire to limit the invention to the specific form shown but intend to cover all modifications, adaptations, and equivalent combinations within the scope of the appended claims.

50 I claim as my invention:

1. In a percussive drill, in combination, a reciprocating percussive member, means responsive to the movement of said member for imparting rotative movement to the same, 55 and means on said member responsive to overload for effecting slip between said first named means and said member.

2. In a percussive drill having a reciprocating impact member, rifle bar mechanism 60 for imparting rotation to said member including a rifle nut carried by the latter, and means permitting slip between said nut and said member when said mechanism is overloaded.

65 3. In a percussive drill having a recipro-

cating impact member, rifle bar mechanism for imparting rotation to said member including a rifle nut rotatably mounted upon said member, and means providing a yielding connection between said nut and said member. 70

4. In a percussive drill having a reciprocating impact member, rifle bar mechanism for imparting rotation to said member including a rifle nut rotatably mounted upon said member, and means providing a yielding connection between said nut and said member arranged to disengage when said mechanism becomes overloaded. 75

5. A piston for a percussive drill having a recess at one end, a rifle nut, means securing said nut in said recess for rotative movement, and means establishing a yielding connection between said nut and said piston. 80

6. A piston for a percussive drill having a recess at one end, a rifle nut, a retainer securing said nut in said recess, and means establishing a yielding connection between said nut and said piston. 85

7. A piston for a percussive drill having a recess at one end, a rifle nut, a retainer securing said nut in said recess and providing a bearing therefor, and a slip connection between said nut and said retainer. 90

8. A piston for a percussive drill having a recess at one end, a rifle nut having a flange at one end, a retainer sleeve for securing said nut in said recess with said flange against the bottom thereof, and a slip connection between said nut and said sleeve. 100

9. A piston for a percussive drill having a recess at one end, a rifle nut, a retainer securing said nut in said recess and providing a bearing therefor, and a spring establishing a slip connection between said nut and said retainer. 105

10. A piston for a percussive drill having a recess at one end, a rifle nut having a flange at one end, a retainer sleeve for securing said nut in said recess with said flange against the bottom thereof, and a spring encircling said flange and arranged to provide a slip connection between said nut and said sleeve. 110

11. A piston for a percussive drill having a recess at one end, a rifle nut having a flange at one end, a retainer sleeve for securing said nut in said recess with said flange against the bottom thereof, and a spring encircling said flange and having reversely directed ends engaging said nut and said sleeve respectively 120 to provide a slip connection between said nut and said sleeve.

12. A rifle nut and retainer for insertion as a unit into a recess in the piston of a fluid pressure tool, said nut and retainer being in telescoping engagement and relatively rotatable, and a flexible coupling therebetween arranged to disengage when a predetermined torque upon either is exerted. 125

13. A rotative unit for threaded insertion 130

into a recess in the piston of a fluid pressure tool comprising an externally threaded sleeve having a smooth central bore, a rifle member rotatably received within said bore and having a radial flange engaging one end of said sleeve, and a flexible coupling between said sleeve and said member arranged to disengage when subjected to a predetermined torque.

14. A rotative unit for threaded insertion into a recess in the piston of a fluid pressure tool comprising an externally threaded sleeve having a recess at one end and a reduced axial bore therethrough, a rifle member having a portion journalled in said bore and a radial flange seated in said sleeve recess, and a spring encircling said flange within said sleeve recess and releasably engaging said sleeve and member to provide a flexible connection therebetween.

15. A retainer for securing a rifle nut in the recessed end of a piston comprising an externally threaded sleeve having a smooth axial bore therethrough and a recess at one end of slightly greater diameter than said bore to receive a radial flange on the rifle nut.

Signed by me at Detroit, in the county of Wayne and State of Michigan, this 2nd day of April, 1929.

GUSTAVE M. NELL.
